UNITED STATES PATENT OFFICE.

GOODRICH Q. LEWIS, OF WHEATON, ILLINOIS, ASSIGNOR TO WILLIAM H. MINER, OF CHICAGO, ILLINOIS,

DRAFT-RIGGING FOR RAILWAY-CARS.

1,070,046.

Specification of Letters Patent. Patented Aug. 12, 1913.

Application filed July 22, 1912; Serial No. 710,844.

To all whom it may concern:

Be it known that I, GOODRICH Q. LEWIS, a citizen of the United States, residing at Wheaton, in the county of DuPage and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a safe, strong and durable draft rigging.

In the accompanying drawings forming a part of this specification Figure 1 is a plan view of a draft rigging embodying my invention. Fig. 2 is a side elevation. Figs. 20 3 and 4 are enlarged details showing the shell and the means of connecting it to the draw bar, Fig. 3 being in side elevation partly in vertical longitudinal section, and Fig. 4 being a plan view.

25 In the drawings 7, 7 represent the center sills of a railway car, or parts of the car frame to which the draft rigging is attached; 8 the end sill; 9 the buffer block; 10 the draw bar carry iron; 11, 11 the front 30 stop members provided with the stop shoulders 12, 12; 13, 13, the rear stop members provided with the stop shoulders 14, 14. The stop members are suitably secured to the center sills by the rivets 15, 15.

35 16, 16 represent horizontal longitudinally disposed guides or plates removably secured to the stop members, the said guides serving to support the draft rigging between the center sills, and upon which the front follower 40 17 and the rear follower 18 slidingly engage. The rear follower 18 is secured to the shell 19, and is preferably integral therewith. The shell 19 is hollow, and preferably cylindrical in shape. It is closed at 45 its rear end 20 by the rectangular rear follower 18, and open at its forward end 21. Within the shell are the compression resisting parts of any suitable form which with the shell form the shock absorbing member of the draft rigging.

50 22 is the means of connecting the shell 19 with the draw bar 23. The draw bar is of the ordinary type, and is provided at its rear end with the transverse slot 24 to receive the preferably flat coupler key 25

which serves to connect the draw bar to the member 22. The member 22 has an upper arm 26 and a lower arm 27, said arms being joined together at their forward ends by the vertical lateral plates 28, 28, forming at the forward end of the member 22 an opening into which the rear end of the draw bar is received.

The plates 28, 28 are each provided with slots 29, 29 for the passage of the coupler key 25. I prefer also to provide slots 30, 30 in the stop members 11, 11, and the center sills 7, 7 suitably horizontally extended to permit the key 25 to reciprocate therein, and to allow its removal and insertion from without the center sills. In preferable construction the lateral plates 28, 28 are forwardly extended, forming the wings 31, 31, which are outwardly flared toward their forward end, as illustrated in Fig. 4 of the drawings, to permit suitable lateral movement of the draw bar.

The arms 26 and 27 extend rearwardly toward the shell, forming between them the transverse opening 32 through which the front follower passes, and are connected to the shell 19 in the manner hereinafter described. The rear face 33 of the front follower 17 reacts in the usual manner against the compression resisting parts within the shell 19. In buffing movement of the draft gear the forward face 34 of the front follower is in engagement with the rear end of the draw bar 23. To permit this engagement the slots 29, 29 in the lateral plates 28, 28 are suitably rearwardly longitudinally extended. The upper and lower arms 26 and 27 extend along the upper and lower forward portions of the shell 19, and are suitably conformed to engage the upper and lower exterior faces of the shell. The arms 26 and 27 are provided near their rear ends with the preferably rectangular slots 35, 35 of suitable dimensions to permit the engagement therein of the oppositely arranged lugs 36, 36 with which the shell 19 is exteriorly provided. The lugs 36, 36 are each of a suitable height to permit the keys or cotters 37, 37 to pass through the transverse perforations 38, 38 provided in the said lugs, and thus secure the arms 26 and 27 against accidental removal from the bosses 36, 36.

In assembling the member 22 and the shell 19 the arms 26 and 27 are spread or sprung sufficiently to slip the slots 35, 35 about the

lugs 36, 36. In removing the member 22 the keys 37, 37 are removed, and the arms 26 and 27 are outwardly sprung sufficiently to permit the disengagement of the lugs 36, 36 from the slots 35, 35.

I claim:-

1. In a device of the character described, a shell, a draw bar and a member connecting the draw bar and shell, said member having rearwardly extending arms, with slots through the said arms, and the shell having external lugs adapted to extend through said slots.
2. In a device of the character described, a draw bar, a shock absorbing member, and a member connecting the draw bar with said shock absorbing member, the said connecting member being provided with upper and lower arms joined at their forward ends by vertical lateral plates forming an opening to receive the draw bar, said arms being provided at their rear ends with slots, and

the shock absorbing member being externally provided with lugs extending within the slots of said arms.

25

3. In a device of the character described, a shell, a draw bar and a member connecting the draw bar and shell, the said member being provided with rearwardly extended arms adapted to be sprung into engagement with the shell.

4. In a device of the character described, a shell, a draw bar and a member connecting the draw bar and shell, the shell being provided with integral lugs, and the said connecting member being provided with rearwardly extended arms provided with slots, the said arms being adapted to be sprung whereby the lugs are brought into engagement within the said slots.
